UNITED STATES PATENT OFFICE

TIMOTHY E. SHEA, OF RUTHERFORD, NEW JERSEY, ASSIGNOR TO WESTERN ELECTRIC COMPANY, INCORPORATED, OF NEW YORK, N. Y., A CORPORATION OF NEW YORK

TRANSMISSION NETWORK

Application filed July 24, 1925. Serial No. 45,792.

This invention relates to electrical networks, and particularly networks comprising elements having natural capacities which act in shunt to the line of transmission of electric energy and has for an object to improve the transmission characteristic of such networks.

In certain types of electric networks, for example electric wave filters, there may exist natural capacities between elements or between some of the elements and ground which capacities act in shunt to the network to increase the loss or to otherwise affect the transmission of some of the frequencies. Such a condition has been found to exist in certain balanced filter structures adapted for use at high voltages where there is a very appreciable capacity existing between each of the high voltage series condensers and ground. These ground capacities in series are effectively in shunt to the filter and greatly distort the transmission characteristic, increasing the loss over a large portion of the transmission range.

In accordance with a feature of this invention there is included in the filter a shunt inductance of such value as to resonate with the two ground capacities in series at a frequency within the transmission band. The impedance of this anti-resonant circuit comprising the two ground capacities and the inductance being very great throughout the transmission range the effect of the condenser is thereby annulled and the transmission characteristic restored to normal. The inductance may consist of a separate coil or may be combined with other inductance elements of the filter in one coil to give the same effect.

In some cases where the disturbing capacities are paralleled by filter condensers, they may be taken into account in determining the capacity of the condensers.

This invention may be more readily understood by referring to the following description in connection with the drawing in which Figs. 1 to 4 show diagrammatically several embodiments of the invention and Fig. 5 the transmission characteristic of the embodiment shown in Fig. 4.

Fig. 1 shows a band pass filter of the type

shown in Fig. 3 of U. S. patent to Campbell 1,227,113 of May 22, 1917, comprising series condensers 7, 7', 8 and 8', series inductances 9, 9', 10 and 10' and a shunt inductance 11. Only a single section is shown and it may be 55 mid series terminated at each end. The filter is of the balanced type each series element being split into two parts, one connected at each side of the line. The series condensers 7 and 7' are adapted to couple to a high voltage line 60 and each is assumed to have an appreciable capacity to ground. These ground capacities are represented by the dotted condensers 12 and 12' which act in series as a shunt across the line and materially increase the loss in the 65 transmission band. In order to counteract their effect an inductance 13, having such a value as to resonate with the capacities 12 and 12' at a frequency within the transmission 70 band, (preferably the mid frequency) is shunted across the line. The impedance of the combination comprising the capacities 12 and 12' and the inductance 13 is substantially infinite at the resonant frequency and very 75 great at all frequencies throughout the transmission band so that the resulting effect is the same as though neither the capacities nor the inductance were present.

In order to reduce the number of elements certain of the inductances may be combined. 80 The method of combining filter elements in this way is fully explained and is claimed in my copending application Serial No. 91,219, filed February 27, 1926. Fig. 2 shows a filter structure in which the inductances 9, 9', 10, 85 10' and 11, are replaced by the equivalent structure consisting of inductances 14, 14', 15 and 16. Inductances 13 and 15 being directly in parallel with one another may be 90 combined in a single coil.

Figure 3 shows another arrangement by which this combination of inductances may be made. In this embodiment the inductances 13, 9, 9', 11, are replaced by the equivalent star structure consisting of inductances 17, 17', 18, 19, 19'. The series inductances 10 and 19 may then be combined in one coil, and similarly inductances 10' and 19'. The annulling inductance 13, does not appear physically; but by virtue of the above men- 95

tioned equivalence of the star structure, it is effectively present and is therefore shown dotted in the position where it effectively acts.

5 Fig. 4 shows another embodiment of this invention in a band pass filter of the type shown in Fig. 1 of U. S. Patent 1,227,113. This filter is also one of the balanced type comprising series condensers 20, 20', 21, and 21', series inductances, 22, 22', 23 and 23', the shunt condenser 24 and the shunt inductance 25. The series condensers 20 and 21' each have appreciable capacities to ground represented by the dotted condensers 26 and 26'. The effect of these condensers is annulled by the use of the shunt inductance 27. In one particular embodiment in a filter for coupling a carrier telephone to a high voltage transmission line, the coupling condensers 20 and 20' are each found to have ground capacities 26 and 26' of .001 mf. The inductance 27 is given a value of 6.2 mh. so as to resonate with the condensers at approximately 92 kilocycles.

25 Fig. 5 shows the transmission characteristic of this filter in which the transmission loss in miles of standard cable is plotted against frequency in kilocycles. Curve A represents the transmission characteristic of the filter section in which series condensers of the same value but having no ground-capacities are substituted for the condensers 20 and 20'. Curve B represents the characteristic for the condensers 20 and 20' having ground 35 capacities. It is seen that with this arrangement the characteristic is badly distorted, the loss being increased over a large portion of the transmission range and the frequency of the lower cut-off being greatly reduced.

40 Curve C shows the filter characteristic of the arrangement in which the annulling inductance 27 is employed.

This is seen to be practically the same as the normal characteristic A of the filter section, the slightly increased loss being largely due to the resistance of the inductance coil.

45 While this invention has been illustrated with only a few specific embodiments, it is understood that it is equally applicable to other circuit arrangements within the scope 50 of the appended claims.

What is claimed is:

1. In a wave-filter adapted to transmit selectively a pre-assigned broad band of frequencies, a condenser included in a series branch of the filter and having stray capacity in shunt to the filter, and a star connected group of inductances adjacent to said condenser, said inductances being proportioned 55 with respect to the capacity of said condenser and to the pre-assigned range of frequencies to maintain the desired selective transmission characteristic, and being proportioned also with respect to said stray capacity to provide 60 a substantially neutralizing reactance there-

for throughout the preassigned frequency range.

2. A wave filter section comprising a pair of series branch impedances coupled by an inductive shunt branch impedance, said series branches including condensers, at least one of which has a stray capacity to ground, and including also inductances which together with said inductive shunt branch form a star connected group, the inductances of said group being proportioned with respect to the capacities of said series condensers and to a preassigned range of frequencies to be selectively transmitted, and also with respect to said stray capacity, 75 whereby said inductance group provides a substantially neutralizing reactance for said stray capacity throughout said preassigned range of frequencies.

In witness whereof, I hereunto subscribe my name this 15th day of July, A. D. 1925.
